[57] CLAIM

The ornamental design for a sterilizer unit, substantially as shown and described.

DESCRIPTION

FIG. 1 is a perspective view showing our new sterilizer unit design, with the cover for the heating well in the closed position;

FIG. 2 is a top plan view thereof;

FIG. 3 is a side elevational view thereof;

FIG. 4 is a front elevational view thereof; and

FIG. 5 is a rear elevational view thereof.

FIG. 1.

FIG. 2.

FIG. 3.

FIG. 4.

FIG. 5.
